UNITED STATES PATENT OFFICE.

CHARLES J. WITHERUP, OF PORT ARTHUR, TEXAS.

PACKING.

Application filed October 19, 1923. Serial No. 689,573.

To all whom it may concern:

Be it known that I, CHARLES J. WITHERUP, a citizen of the United States, residing at Port Arthur, in the county of Jefferson 5 and State of Texas, have invented certain new and useful Improvements in a Packing, of which the following is a specification.

This invention appertains to an improved packing for pistons, piston rods, stuffing 10 boxes and the like and the primary object of the present invention is to provide a strong and durable packing, which will positively reduce leakage and effectively prevent wear on the parts which it engages.

Another prime object of the invention is to provide an improved packing which will stand up under all conditions and effectively prevent leakage irrespective of the kind of fluid with which the packing is used.

A further prime object of the invention is to provide an improved packing ring embodying an annular cork body for engaging the surface directly, which is to be packed, the cork body providing a fluid type packing surface 25 and also means for preventing wear on the moving part, in view of the fact that the body presents a substantially frictionless surface.

A further prime object of the invention 30 is to provide an improved packing embodying a rubberized duck or asbestos filled container having an annular channel therein for receiving the cork packing body, the rubberized duck or asbestos filled container 35 forming means for creating a continuous pressure against the cork packing body in view of the fact that the said rubberized fabric or asbestos filled container will swell, when in use.

A still further prime object of the invention 40 is to provide an improved packing of the above character, which will be durable and efficient in use, one that will be simple and easy to manufacture and to install and one which can be placed upon the market at a small cost.

With these and other objects in view, the invention consists in the novel construction, arrangement and formation of parts, as will 50 be hereinafter more specifically described, claimed and illustrated in the accompanying drawings, in which drawings:

Figure 1 is a perspective view of the improved packing ring constructed in accordance 55 with this invention for use on a moving part such as a piston.

Figure 2 is a perspective view of a packing constructed in accordance with this invention when used for an immovable part.

Figure 3 is a diametric section through 60 the movable packing ring, and

Figure 4 is a diametric section through the immovable packing ring.

Referring to the drawings in detail, wherein in similar reference characters designate 65 corresponding parts throughout the several views, the letter A generally indicates the movable packing ring and B the immovable packing ring.

The packing ring A comprises an outer 70 body 5, which can be formed of a plurality of plies of fabric, such as duck, canvas or the like and the fabric is adapted to be impregnated with rubber or some other similar material. If so desired the outer body 75 5 can be formed of asbestos fibre or the like. This body 5 can be folded or otherwise formed to provide an outer channel 6 and the body when folded is substantially U-shaped in cross section and defines upper 80 and lower spaced parallel annular walls 7 and an inner connecting annular wall 8. If so desired a rubber cushion 9 can be incorporated in the inner connecting wall 8. The channelway 6 is adapted to receive the cork 85 packing ring 10 which forms the most important feature of this invention, as will be hereinafter more fully described.

The immovable packing ring B is constructed substantially the same as the packing ring A and includes the outer body 15 which is also formed of a plurality of plies of fabric such as duck or the like impregnated with rubber, or this body 15 can be formed of asbestos. The body 15 is folded or otherwise formed substantially U-shaped in cross section. This provides upper and lower spaced parallel walls 17 and an outer annular connecting wall 18 which can be provided with a rubber cushion 19 if so desired. The channel 16 is arranged to receive the solid cork packing ring 20.

It can be seen that the two packing rings A and B are of substantially the same construction with the exception that the cork 105 ring 10 of the packing ring A is disposed at the outer periphery of the packing ring, while the cork ring 20 is disposed at the inner periphery of the packing ring B.

The use of cork as the packing medium 110 fulfills a long felt want in the packing art, in view of the fact that packing rings now

on the market under certain trying conditions will not stand up and permit the leakage of certain fluids. Further certain packing rings cause great wear on the moving parts, which result in loss of power.

The cork packing ring forms an ideal packing, as the same provides almost a frictionless surface which will prevent wear but which at the same time provides a snug fit 10 for preventing leakage of all kinds of fluids.

Whether the outer body of the packing is to be made of rubberized fabric or woven asbestos, depends upon the use to which the packing is to be put and it is obvious that 15 when the packing is to be used on devices handling acids and caustics, that asbestos is best suitable.

While I prefer to provide a body provided with a complete channel for receiving the cork packing ring in view of the fact that the body will swell and tightly hold the ring in place, it is to be understood that the outer body can be eliminated and simply rings of asbestos or rubberized duck 25 sewed or otherwise secured to the opposite faces of the cork.

From the foregoing description, it can

be seen that I have provided an improved packing of simple and durable construction which will effectively prevent leakage of 30 all kinds of fluids.

Changes in details may be made without departing from the spirit or the scope of this invention.

What I claim as new is:

A packing of the class described, comprising an annular cork ring rectangular in cross section and an annular channel shaped covering, the web of the channel extending across and fitting closely against 40 one of the cylindrical surfaces of the cork and the legs of the channel extending over and fitting closely against the respective flat faces of the cork ring, said legs terminating flush with the remaining cylindrical face 45 of said cork ring, said covering consisting of material adapted to swell when in use, and a rubber cushion imbedded in the web of the channel shaped covering and extending concentric to the ring in spaced relation 50 thereto.

In testimony whereof I affix my signature.

CHARLES J. WITHERUP.
